TELEPHONE SIGNAL CONTROL UNIT

Felix Gilbert, New York, N.Y., assignor to General Alarm Corporation, New York, N.Y., a corporation of Delaware

Filed Oct. 24, 1966, Ser. No. 4,405

Term of patent 14 years

(Cl. D26—13)

FIG. 1 is an elevational view of a telephone signal control unit embodying my new design;

FIG. 2 is a side elevational view of the unit illustrated in FIG. 1;

FIG. 3 is a top plan view of said unit; and

FIG. 4 is a fragmentary cross sectional view taken along the lines 4—4 of FIG. 1.

I claim:

The ornamental design for a telephone signal control unit, as shown.
